GRINDING GAUGE

Albert Klepal, Coraopolis, Pa.

Application June 28, 1949, Serial No. 101,761

5 Claims. (Cl. 51—165)

1

This invention relates to an improved gauge, for use with a grinding wheel, turning lathe, or the like, the primary object of the invention being to provide a gauge of this character which moves with the grinding wheel, lathe tool or the like across the work and indicates at all times during the grinding or machining, the amount of stock remaining to be removed, and the actual diameter of the work being ground or machined, while at the same time taking into consideration wear of the grinding wheel or turning tool, which is an important factor, particularly in finish cuts.

Another important object of the invention is the provision of a gauging device of the above indicated character which enables avoidance of grinding cylindrical portions undersize.

Another important object of the invention is to provide a device of the above indicated character which enables the operator of the grinding machine or the like to maintain a constant accurate check on the progress of the grinding or machining without interruptions to the process otherwise necessary for micrometer or other ordinary gauge checks.

Other important objects and advantageous features of the invention will be apparent from the following description and appended drawings, wherein, merely for present purposes of illustration, specific embodiments of the invention are set forth in detail.

In the drawings:

Figure 1 is a side elevation showing the illustrated device applied to a grinding machine and associated cylindrical work piece.

Figure 2 is an enlarged perspective view of the diameter arm.

Figure 3 is a group perspective view of the components of the depth arm.

Figure 4 is a perspective view of the radius arm.

Figure 5 is a group perspective view of the components of the gauge section.

Figure 6 is a perspective view of the assembled gauge section and radius arm; and,

Figure 7 is a fragmentary side elevation of a modified form.

Referring in detail to the drawings, the numeral 9 generally designates a grinding machine having the grinding wheel 10 partially enclosed at the top by the guard 11. In the form of the invention shown in Figure 1, the guard 11 has fixed to rise therefrom a stationary standard or bracket 12 traversed by a clamping bolt 13. The bolt 13 passes through a longitudinally elongated slot 14 formed within the ends of a flat elongated substantially horizontal diameter arm 15 terminat-

ing at one end in the bifurcation 16. The bifurcation is apertured at 17 to pass a handled clamping bolt or screw 18.

The vertical depth arm 19 depends from the bifurcated forward end of the diameter arm and is composed of a vertically elongated plate 20 having a raised portion 21 on one side near its upper end defining a shoulder 21', an apertured ear 22 on its upper end received in the bifurcation 16 on the diameter arm 15 and traversed by the clamping bolt 18, and the longitudinal runner 23 on the same side as the raised portion 21.

The depth arm 19 further comprises the vertically elongated plate 24 formed with a longitudinal slot 25 longer than the runner 23, and further formed with a raised portion 26 on one side formed as an apertured bifurcation 27. The runner 23 slides in the slot 25 and the plates 20 and 24 are maintained in superimposed sliding relation by a headed screw 28 passing through the slot 25 and threaded into the runner 23.

The gauge section, generally designated 30 is supported from the bifurcated lower end of the depth arm 19 by a bolt 31 traversing the bifurcation 26 and the arm 32 of the right angled radius arm 33. The remaining arm 34 of the radius arm 33 is longitudinally slotted at 35 to accommodate a clamping screw 36 on an overlying portion 36' secured to the gauge section 30.

As shown in Figures 5 and 6, the gauge section 30 comprises a vertically elongated base plate 37 formed in one side with a longitudinal vertical channel or slideway 38 opening at its upper end through the side of the plate 37 as indicated at 39. Slidable longitudinally in the slideway 38 is the flat gauge shoe body 40 having at its upper end a lateral pin 41 working through the opening 39 and at its lower end a work engaging shoe 42 having an extension 43 projecting on the side of the body 40 opposite the pin 41. The lower transverse edge 44 is rounded as indicated to traverse the work piece 45 longitudinally and pass work cuts with minimum friction and catching in the work cuts. An expanding helical spring 46 is interposed between the abutment 47 at the upper end of the slideway 38 and the upper end of the body 40 whereby the body 40 is urged downwardly in the slideway 38 toward a position in which the pin 41 is at the lower end of the opening 39 and the shoe 42 is spaced below the lower end of the base plate 37.

The gauge section 30 further comprises the cover plate 48 apertured along its edges to pass screws 49 securing the cover plate to the base plate 37 and confining the shoe body 40 in place,

The cover plate has the lateral arm or portion 36' which is adjustably secured to the arm 34 of the radius arm 33 by the screws 36. On the same side as the arm 36' the cover plate 48 has a horizontal bubble level 49. The abutment 47 at the upper end of the base plate 37 has openings 50, 50 to accommodate the plunger of a dial indicator 51 mounted thereon, to be operated by the slide plate 40.

In the form of the invention shown in Figure 7, the support of the diameter arm 15 is modified to include a pin 52 on a horizontally elongated portion 53 of the bracket 12' and working in the slot 14 of the diameter arm 15, and a vertically elongated slot 54 in the bracket provided in one edge with equally spaced notches 55 arranged to selectively receive therein a handled clamping bolt 13', corresponding in effect to the clamping bolt 13 of Figure 1, with the clamping bolt 13' passing through the slot 14 of the diameter arm 15. This arrangement provides for easier rough adjustment of the horizontal angulation of the diameter arm 15.

In using the device of the invention, the device is mounted as indicated on the bracket 12 or 12' and the diameter arm 15 is then set, by loosening the clamping bolt 13 or 13' and extending or retracting and angulating the arm 15 to place the gauge section 30 at the center of the work piece 45 and at a sufficient height to clear the shoe 42 from the top of the work piece 45. The depth arm 19 is then adjusted for the correct clearance of the shoe 42 with the top of the work piece. Adjustment of the radius arm 33 is needed only when radius wheels are in use. On plain flat work the gauge section can be in any position on the radius arm.

In setting the device it is necessary to have the gauge section 30 perpendicular, as indicated by the bubble level 49. The bubble level 49 is parallel to the shoe 42 so that a proper setting assures the shoe being perfectly tangent to the work piece 45 and horizontal, or vertically centered with respect to the work piece 45, the spring 46 then acting to keep the shoe 42 in constant accurate contact with the work piece 45. This "on center" positioning of the shoe 42 allows for grinding wheel wear as well as for depth of cut.

Accurate grinding of cylindrical portions is assured by the riding of the shoe 42 across the work piece, since thereby the dial indicator 51 thereby constantly indicates not only the depth of cut but also the parallel of the work piece being ground.

The above described device can be readily adapted to use with machines of different sizes and forms and work pieces of different sizes by adjusting the components relative to each other. The components also lend themselves readily to variation in size and shape to adapt the device to different types of work and machines such as lathes, Hypros, and large boring mills.

What is claimed is:

1. In combination, a grinding gauge and a grinding machine having a grinding wheel and a wheel guard, a bracket fixed to rise from said guard substantially in the plane of the grinding wheel, a generally horizontal diameter arm projecting from said bracket beyond the grinding wheel to a point substantially perpendicularly above the center of a work piece to which the grinding wheel is applied, a depth arm secured to depend from the forward end of said diameter arm, a gauge section mounted on the lower end of said depth arm comprising a base plate, a ver-

tically movable downwardly spring pressed plate mounted thereon having a shoe to constantly contact the work piece on a vertical center, and an indicator on said base plate operated by displacement of said movable plate relative to said base plate, releasable clamping means mounting said depth arm on the forward end of said diameter arm and providing for angulation of said depth arm relative to said diameter arm to enable more accurate centering of said gauge section relative to the workpiece than provided by an adjustment of said diameter arm, said depth arm comprising elements vertically adjustable relative to each other to enable more accurate contacting of the gauge section shoe with the work piece than provided by an adjustment of said diameter arm.

2. In combination, a grinding gauge and a grinding machine having a grinding wheel and a wheel guard, a bracket fixed to rise from said guard substantially in the plane of the grinding wheel, a generally horizontal diameter arm projecting from said bracket beyond the grinding wheel to a point substantially perpendicularly above the center of a work piece to which the grinding wheel is applied, a depth arm secured to depend from the forward end of said diameter arm, a gauge section mounted on the lower end of said depth arm comprising a base plate, a vertically movable downwardly spring pressed plate mounted thereon having a shoe to constantly contact the work piece on a vertical center, and an indicator on said base plate operated by displacement of said movable plate relative to said base plate, a transverse bubble level on said base plate and releasable clamping means connecting the lower end of said depth arm to said gauge section whereby said gauge section can be adjusted relative to said depth arm and said diameter arm into perpendicular relation to the center of the work piece.

3. In combination, a grinding gauge and a grinding machine having a grinding wheel and a wheel guard, a bracket fixed to rise from said guard substantially in the plane of the grinding wheel, a generally horizontal diameter arm projecting from said bracket beyond the grinding wheel to a point substantially perpendicularly above the center of a work piece to which the grinding wheel is applied, a depth arm secured to depend from the forward end of said diameter arm, a gauge section mounted on the lower end of said depth arm comprising a base plate, a vertically movable downwardly spring pressed plate mounted thereon having a shoe to constantly contact the work piece on a vertical center, and an indicator on said base plate operated by displacement of said movable plate relative to said base plate, a transverse bubble level on said base plate and releasable clamping means connecting the lower end of said depth arm to said gauge section whereby said gauge section can be adjusted relative to said depth arm and said diameter arm into perpendicular relation to the center of the work piece, said releasable clamping means comprising a radius arm comprising means for adjusting said gauge section laterally with respect to the vertical plane of the grinding wheel and laterally with respect to said depth arm.

4. In combination, a grinding gauge and a grinding machine having a grinding wheel and a wheel guard, a bracket fixed to rise from said guard substantially in the plane of the grinding wheel, a generally horizontal diameter arm projecting from said bracket beyond the grind-

ing wheel to a point substantially perpendicular-
ly above the center of a work piece to which the
grinding wheel is applied, a depth arm secured to
depend from the forward end of said diameter
arm, a gauge section mounted on the lower end
of said depth arm comprising a base plate, a
vertically movable downwardly spring pressed
plate mounted thereon having a shoe to con-
stantly contact the work piece on a vertical
center, and an indicator on said base plate op-
erated by displacement of said movable plate re-
lative to said base plate, releasable clamping
means mounting said diameter arm on said
bracket and permitting longitudinal adjustment
of said diameter arm relative to said bracket and
angulation of said diameter arm relative to said
bracket to provide for vertical centering of said
gauge section relative to the work piece and on
center contact of said gauge section shoe with the
work piece, said releasable clamping means com-
prising a clamping bolt on said bracket and
passing through a longitudinal slot formed in
said diameter arm.

5. In a grinding gauge for a grinding machine
having a grinding wheel and a wheel guard, a
bracket adapted to be fixed to rise from said
guard substantially in the plane of the grinding
wheel, a generally horizontal diameter arm
projecting from said bracket beyond the grind-
ing wheel to a point substantially perpendicularly
above the center of a work piece to which the
grinding wheel is applied, a depth arm secured
to depend from the forward end of said diameter
arm, a gauge section mounted on the lower end
of said depth arm comprising a base plate, a
vertically movable downwardly spring pressed
plate mounted thereon having a shoe to con-
stantly contact the work piece on a vertical

center, and an indicator on said base plate op-
erated by displacement of said movable plate re-
lative to said base plate, releasable clamping
means mounting said diameter arm on said
bracket and permitting longitudinal adjustment
of said diameter arm relative to said bracket and
angulation of said diameter arm relative to said
bracket to provide for vertical centering of said
gauge section relative to the work piece and on
center contact of said gauge section shoe with the
work piece, said releasable clamping means com-
prising a pin projecting laterally from said
bracket and through a longitudinal slot formed
in said diameter arm, a clamping bolt carried
by said diameter arm and projecting through
said slot, said bracket being formed with a
vertical opening displaced from said pin to-
ward the forward end of said bracket, said open-
ing being formed along one vertical edge there-
of with spaced notches arranged to selectively
receive said clamping bolt to position said diam-
eter arm in a vertical plane at different angles
with respect to the horizontal.
